his Attorney

UNITED STATES PATENT OFFICE.

AUGUST G. SANDMAN, OF BALTIMORE, MARYLAND.

JOURNAL BOX.

Application filed August 2, 1922. Serial No. 579,263.

To all whom it may concern:

Be it known that I, AUGUST G. SANDMAN, a citizen of the United States, residing at Baltimore, in the State of Maryland, have 5 invented certain new and useful Improvements in Journal Boxes; and I do hereby declare the following to be a full, clear, and exact description of the invention, such as will enable others skilled in the art to which

10 it appertains to make and use the same.

My invention relates to journal boxes and, generally stated, involves the provision of a renewable wear plate or liner detachably connected to the journal box of a railway 15 car for preventing destructive wear upon the car truck pedestal jaws and journal box associated therewith.

The principal feature of the present invention, particularly stated, resides in the 20 production of a journal box having tapered pedestal guide ways, and associating therewith a liner or wear plate adapted to fit within the tapered guide ways.

Another feature of the invention consists 25 in tapering the wear plate or liner laterally of the journal box from a lesser width near the center to a slightly greater width at the top and bottom thereof, whereby said journal box can move laterally in the pedestal ways, said movement involving in addition to the relative vertical movement of the journal box pedestal jaws, a relative 30 rocking or pivotal movement of said journal box and pedestal incident to axle thrusts and the like.

Another feature of the invention is to 35 provide a flanged liner for journal boxes for pedestal trucks, the flanged portion of said liner being tapered to effectively retain the liner in engagement with the journal box and provide lateral clearance for pivotal 40 movement of said journal box with respect to the pedestal jaws.

A further feature of the invention consists 45 in combination, a journal box having a reservoir adapted to receive a lubricant such as oil, a wear plate or liner adapted to be connected to said journal box for permitting relative pivotal movement between the pedestal jaws and the journal box, and means for establishing communication between the oil reservoir and the wearing surface of the liner whereby lubricant is permitted to flow to said wearing surface.

55 The invention further consists in the pro-

vision of a journal box renewable pedestal way flanged liner which can be inexpensively manufactured and easily attached to a journal box adjacent an oiling cavity preferably in the top of said journal box. 60

There are other features of the invention as will more clearly appear from the detailed description taken in connection with the accompanying drawings in which

Figure 1 is a view in side elevation of a 65 railway car journal box showing my improved wear plate or liner applied.

Figure 2 is a vertical detail sectional view on the line 2—2 of Figure 1 through a portion of the journal box and oil reservoir at 70 the top thereof.

Figure 3 is a detail horizontal sectional view on the line 3—3 of Figure 1 showing the flanged liner cooperatively associated with opposite faces of the journal box 75 flanges.

Figure 4 is a detail central vertical transverse sectional view through the upper portion of the journal box illustrating the oil reservoirs and the attaching tongues of the 80 liner engaging the walls of the reservoirs.

Referring to the drawings in which similar reference characters designate corresponding parts in the several views, the railway car journal box is indicated by the numeral 1, said journal box being provided with the top wall 2 in which is formed the seat 3 adapted to receive the cushioning element, and the usual bottom wall 4. The opposite side walls 5—5 of the journal box 90 are each provided with projecting adjacent ribs or flanges 6, each of which is tapered laterally of the journal box so as to provide a lesser width between the flanges at or near the center thereof, than between said flanges 95 at the top and bottom edges. The tapering flanges 6 and side wall portions of the journal box are formed with a guide way in which is provided a clearance between the pedestal jaws and the journal box flange, 100 said clearance permitting relative pivotal or rocking movement between the journal box and pedestal. The inner opposed faces of adjacent flanges 6 are inclined from the top and bottom edges thereof respectively, toward the center, portions of said flanges extending out into the pedestal guide ways 105 to form extensions in the nature of fulcrum points 7.

A flanged wear plate 8 is adapted to fit 110

within and line said pedestal guide way, the flanges 9 thereof being tapered to fit the tapered portions of the flanges 6 formed on the journal box. The liner, and more particularly the flanges 9 thereof, is tapered or inclined laterally of the journal box from a lesser width near the center to a slightly greater width at the top and also at the bottom thereof, the taper or incline 10 of said flanges corresponding to the tapered portions of the journal box side wall flanges 6 with which latter the flanges 9 of the liner engage.

The web or body portion 10 of the wear plate is arranged to engage the side wall portion of the journal box adjacent the projecting flanges 6, as clearly shown in Figure 3. The wearing surface of the web portion and adjacent flanges 9 are lubricated 15 by means of oil or other lubricant, said lubricant being contained within a reservoir or cavity 11 preferably at the top of the journal box, an upstanding surrounding wall portion 12 serving to retain the oil. In 20 the form of journal box shown I have provided a plurality of oil reservoirs, one on each side of the cushioning element seat, as shown, although it will be understood that a single reservoir may be used in some constructions.

Provided near the bottom of each reservoir is an opening 13, said opening being adapted to communicate with an opening 14 formed in the web portion of the wear plate, 25 and it is through these registering openings that the oil or lubricant is conveyed to the wearing surface of the liner. Each opening 14 in the wear plate is preferably provided near the top thereof and adjacent the oil 30 reservoir so as to provide for the gravitation of the oil over the wearing surface of the liner. The wear plate is shown as formed with two openings, each of said openings, each of said openings being located relatively close to the adjacent flange 9 of the liner. In the type of journal box shown the liner is cut away intermediate 35 said openings, as indicated by the numeral 15, so as to fit the journal box side wall beneath the offset portion therein provided for the clearance of the equalizer bar, not shown.

The means for detachably connecting the wear plate to the journal box includes upper bendable extensions 16 forming tongues or tangs adapted to be bent over the upper edge of the wall portion, said tangs extending downwardly substantially parallel with the wearing surface of the liner. Bendable 40 extensions 17 are formed on the lower edge of the liner, said extensions forming tongues or tangs adapted to be bent around the lower edge of the journal box side wall, as shown. Other types of attaching means may be utilized, as will be understood. It will be

seen that the tapering of the wear plate flanges 9 inwardly from the respective top and bottom edges thereof serves to retain the liner in engagement with the journal box, thereby supplementing the upper and lower connecting tangs.

From the foregoing description it will be apparent that I have provided a journal box having a tapered pedestal guide way adapted to be lined with a tapered flanged wear plate whereby relative rocking movement incident to service conditions can be effectively permitted, and which, together with the adjacent means for lubricating, the wearing surface of said wear plate, serves to materially reduce the strain and wear and increase the longevity of use of the associated parts.

I claim:

1. The combination with a railway car 95 journal box having a pedestal guide way the side walls of which are outwardly flared, and a wear plate or liner adapted to engage said tapered guide way.

2. The combination with a railway car 90 journal box provided with a pedestal guide way tapered from the top and bottom thereof toward the center, and a wear liner adapted to engage and fit within said tapered guide way.

3. The combination with a railway car journal box having a pedestal guide way tapered from one end thereof toward the center, and a wear liner adapted to engage and fit within said tapered guide way.

4. The combination with a railway car journal box provided with projecting flanges forming a tapered pedestal guide way, each of said flanges being arranged at an angle to a vertical plane at right angles 105 to the axis of the journal box, and a wear plate adapted to fit said projecting flanges.

5. The combination with a railway car journal box provided with projecting flanges, each of said flanges being tapered from one end thereof toward the center and adapted to form with the side wall of said journal box a pedestal guide way, and a liner adapted to engage said flanges and the side wall of the journal box.

6. The combination with a railway car journal box having a side wall, of flanges adjacent said side wall forming pedestal ways, each of said flanges having a portion projecting out into the pedestal way at the center thereof, and a wear plate for said journal box, said wear plate being provided with portions adapted to engage the flanges projecting from the journal box side wall.

7. The combination with a railway car journal box having a side wall, of flanges adjacent said wall forming pedestal ways, each of said flanges being inclined inwardly of the pedestal way from both the top and bottom ends thereof, and a wear plate hav-

- ing flanges similarly inclined and adapted to engage the flanges on the journal box.
8. The combination with a railway car journal box having a side wall, of flanges adjacent said wall forming pedestal ways, said flanges being tapered laterally of the journal box from a lesser width near the center to a greater width at both the top and bottom thereof, and a flanged liner formed with similarly tapered portions adapted to engage the flanges of the journal box.
9. The combination with a railway car journal box having a side wall, of flanges adjacent said wall forming pedestal ways, said flanges being tapered laterally of the journal box from a lesser width near the center to a greater width at both the top and bottom thereof, a liner having portions adapted to engage said tapered flanges, and means provided on said liner for detachably connecting the same to the journal box.
10. The combination with a railway car journal box having a side wall, of flanges adjacent said wall forming pedestal ways, and a wear plate having flanges adapted to engage the journal box flanges, each of said wear plate flanges being tapered laterally of the journal box and inwardly toward each other from both the top and bottom edges of said wear plate.
11. The combination with a railway car journal box having a side wall, of flanges adjacent said side wall forming pedestal ways, a wear plate having flanges adapted to engage the journal box flanges, each of said wear plate flanges being tapered laterally of the journal box, and means provided on the ends of said wear plate for attaching the same to the journal box.
12. The combination with a railway car journal box having a tapered pedestal guide way, a wear plate or liner adapted to engage said tapered guide way, and means including an oil reservoir at the top of said journal box for lubricating the wearing surface of said liner.
13. The combination with a railway car journal box provided with a pedestal guide way, a liner adapted to engage said guide way, said liner having an opening near its upper end, and an oil reservoir carried by said journal box and having an opening communicating with said opening in the liner for conveying lubricant to the wearing surface of said liner.
14. The combination with a railway car journal box having a pedestal guide way, a liner having an opening, said liner being fitted within the pedestal guide way, and means including an oil reservoir carried by the journal box for conveying oil through the opening in said liner to the wearing surface thereof.
15. The combination with a railway car journal box having a pedestal guide way, of a flanged wear plate connected to said journal box and fitted within said guide way, and means involving an oil reservoir carried by said journal box for conveying oil to the wearing surface of said flanged wear plate.
16. The combination with a railway car journal box provided with a tapered pedestal guide way, a flanged liner having tapered portions adapted to engage said tapered guide way, an oil reservoir carried by said journal box, and means for establishing communication between said reservoir and the wearing surface of said liner.
17. The combination with a railway car journal box having a side wall, of flanges adjacent said side wall forming pedestal ways, each of said flanges having a portion projecting out into the pedestal way, a wear plate for said journal box, said wear plate being provided with an opening adapted to engage the flanges projecting from the journal box side wall, and means involving an oil reservoir for conducting lubricant to the wearing surface of said wear plate.
18. The combination with a railway car journal box having a side wall, of flanges adjacent said side wall forming pedestal ways, a flanged wear plate connected to said flanges, said wear plate having an opening adjacent each flange, and oil reservoirs each provided with an opening adapted to permit the flow of oil therethrough to each of said openings in the wear plate for conveying the lubricant to the wearing surface of the plate.
19. The combination with a railway car journal box, having a side wall, of flanges adjacent said side wall forming a tapered pedestal way, a tapered liner adapted to engage said pedestal way, said liner having an opening near the top thereof, and an oil reservoir adapted to permit the flow of lubricant through said opening to the wearing surface of the liner.
20. The combination with a railway car journal box having an oil reservoir and a flanged liner connected to said journal box, said liner having openings at the top of the wearing surface communicating with said oil reservoir, each of said openings being arranged near an adjacent flange and adapted to permit the flow of oil to the wearing surface of said liner.
21. In combination, a journal box for railway cars provided with an oil cavity, a wear plate connected to said journal box, and means for conducting oil from said reservoir to the wearing surface of said wear plate.
22. In combination, a journal box for railway cars having a walled portion at the top thereof adapted to form an oil reservoir, said walled portion having an open-

- 1 ing adapted to permit the discharge of the oil from said reservoir, a wear plate provided with an opening adapted to register with said reservoir discharge opening, and 5 means for attaching said wear plate to the journal box, said attaching means being adapted to engage a portion of the wall forming said oil reservoir.
23. In combination a journal box for 10 railway cars having a walled portion at the top thereof adapted to form an oil reservoir, said walled portion having an opening adapted to permit the discharge of the oil from said reservoir, a wear plate provided with an opening adapted to register 15 with said reservoir discharge opening, and means including a bendable tang adapted to be bent about said walled portion and arranged to lie substantially parallel with 20 the wearing surface of the plate.
24. A wear plate of the class described comprising a body portion having a wearing surface and adjacent flanges, said flanges being tapered with respect to each 25 other from a lesser width near the central portion of the wear plate to a greater width at the top and bottom portions thereof.
25. A wear plate of the class described comprising a body portion having a wearing 30 surface and adjacent flanges, each of said flanges being inclined laterally of the plate from a vertical plane extending from the top of said plate to the bottom thereof.
26. A flanged wear plate of the class described involving a web portion, said web 35 portion having a wearing surface formed with an opening adapted to form a lubri-
- cating duct, and flanges adjacent said web portion.
27. A flanged wear plate of the class described involving a web portion, said web portion having a wearing surface formed with an opening adapted to form an oil duct, and flanges adjacent said web portion, each of said flanges having a portion extending laterally of the plate. 40
28. A flanged wear plate of the class described involving a web portion having an opening, and flanges adjacent said web portion, each of said flanges having portions 50 inclined from a vertical plane extending from the top of said plate to the bottom thereof.
29. A flanged wear plate of the class described involving a web portion, said web portion having a wearing surface formed with an opening, tapered flanges adjacent said web portion, and bendable extensions provided at the opposite ends of said web portion forming an attaching means for 55 the wear plate.
30. The combination with a railway car journal box having a pedestal guide way and reservoir adapted to receive lubricating material, of a wear plate for said guide way, and means including a portion of the journal box arranged to engage the wear plate, said portion being provided with an opening communicating with said reservoir and adapted to convey lubricating material 60 to the wearing surfaces of the wear plate. 65

In testimony whereof I affix my signature.

AUGUST G. SANDMAN.
